UNITED STATES PATENT OFFICE.

RUDOLPH E. BRUCKNER, OF NEW YORK, N. Y.

SAFETY MEANS FOR AUTOGENOUS WELDING OR CUTTING APPARATUS.

1,227,881.

Specification of Letters Patent.

Patented May 29, 1917.

Application filed January 26, 1917. Serial No. 144,611.

To all whom it may concern:

Be it known that I, RUDOLPH E. BRUCKNER, a citizen of the United States of America, residing at New York city, county and State of New York, have invented a new and useful Safety Means for Autogenous Welding or Cutting Apparatus, of which the following is a specification.

My invention relates to gas welding or cutting apparatus and particularly to a safety apparatus therefor.

In the accompanying drawing:

Figure 1 is a conventional view of the upper part of two gas tanks operatively connected and associated with a torch, certain parts being shown in section.

Fig. 2 is a relatively enlarged sectional view on the line 2—2, Fig. 1.

Fig. 3 is a cross section on the line 3—3, Fig. 2.

It should be understood at the outset, that I shall describe herein only one preferred form and arrangement of my invention. 1 conventionally represents the upper part of an acetylene tank. 2 conventionally represents the upper part of an oxygen tank. 3 is a pipe leading from the acetylene tank to a welding or cutting torch, the burner end of which is conventionally illustrated at 4. 5 represents a pipe leading from the oxygen tank to said torch. 6 is a pressure regulating valve in the line 5, while 7 is a pressure regulating valve in the line 3. 8 is a gage to indicate the pressure in the line 5 beyond the valve 6. 9 is a gage to indicate the pressure in the line 3 beyond the valve 7. 10 is a gage to indicate the pressure in the line 5 between the interior of tank 2 and valve 6. 11 is a gage to indicate pressure in the line 3 between tank 1 and valve 7. In practice, in an apparatus of this character it is rare to set the pressure regulating valves 6—7 so as to operate at the same pressure. For example, in using a torch having a relatively large welding tip, one would naturally set the oxygen pressure say between twenty and thirty pounds, while he would set the acetylene pressure at between three and ten pounds. Under these conditions for example, if the point of egress of the mixed gases from the torch 4 should be momentarily stopped or choked, the gas in the line 3 or 5 which is under highest pressure

would force back through the other line 5 into the other tank. For example, if the oxygen in the line 5 were at a higher pressure than the acetylene in the line 3, a stoppage at the point of egress from the torch would cause the oxygen to flow through the line 3 against the lower pressure past the valve 7 and into tank 1. It is a well known fact that any mixture of gases under pressure invites grave dangers, it being much more easy to explode a tank charged with a mixture of such gases under pressure than to explode the tank containing only one of said gases in a pure state under pressure. Indeed, many explosions have occurred from a supposedly unknown cause, some of which may be readily attributed to this particular cause. It is my object to prevent this transfer of gas from one tank to the other, and this I accomplish by providing suitable mechanism somewhere between the interior of each of said tanks respectively and the point of merging of the gases therefrom, which mechanism operates to positively prevent the aforesaid action. In Fig. 2 I have shown on an enlarged scale a portion of the line 3, in which figure 12 represents a cylindrical valve chamber. This valve chamber is provided with a nipple extension 14 at one end having a passage therethrough, the inner end of said nipple forming a valve seat. 15 is a valve mounted in the valve chamber 12, said valve operating to close the passage against the flow of gas therethrough excepting to the torch. 16 is a spring by which the valve 15 may be assisted in its operation. 17 is a movable nipple which is screw threaded into the valve casing 12 and by which access may be had to the valve 15 or spring 16. The gas line in the main may be made of any flexible tubing which may be secured over the nipples 14—17. By putting the mechanism shown in Fig. 2 in the pipe line 3, with the point of the valve 15 directed toward the tank 1 and by providing a corresponding mechanism at 18 in the other pipe line 5, with the point of the valve therein directed toward the tank 2, it is obvious that it is absolutely impossible for the pressure of gas in one pipe line, no matter how much greater its pressure may be than the pressure in the other line, to cause a transference of gas from one tank

to the other. 19—19^a are stop cocks on the respective gas lines 3 and 5, which may be provided if desired.

It will be understood that my invention is not limited to the use of any particular gas or gases in the tanks 1 and 2, but I refer to oxygen and acetylene as those most commonly used in this particular connection and those in which grave danger lies in the absence of the safety means disclosed herein.

What I claim is:

1. In an apparatus of the character described, two receptacles for containing different gases under pressure, a torch, flexible means of communication from said receptacles to said torch the communicating passages merging, pressure regulating mechanism for regulating the relative pressure of gas in said communicating passages, and

means in said flexible communicating means to prevent the flow of gas from one tank into the other.

2. In an apparatus of the character described, two receptacles for containing different gases under pressure, a torch, flexible means of communication from said receptacles to said torch the communicating passages merging, pressure regulating mechanism for regulating the relative pressure of gas in said communicating passages, and means in said flexible communicating means to prevent the flow of gas from one tank into the other, said last mentioned means comprising a cylindrical valve chamber 30 having a passage therethrough, a nipple extension at each end of said chamber and a check valve in said chamber. 35

RUDOLPH E. BRÜCKNER.
